CLAIM

The ornamental design for a protective pad for use with shoulder straps, as shown and described.

DESCRIPTION

FIG. 1 is a perspective view of the present invention;
FIG. 2 is a front elevational view of the present invention;
FIG. 3 is a right side elevational view of the present invention;

FIG. 4 is a top plan view of the present invention;
FIG. 5 is a bottom plan view of the present invention; and,
FIG. 6 is a left side elevational view of the present invention.
